County, Ohio

Application May 1, 1940, Serial No. 332,795

11 Claims. (Cl. 206—12)

This invention relates to improvements in first aid kits of the so-called field type.

An object of the present invention is to provide a first aid kit which when closed presents a sturdy, compact easily portable unit adapted to withstand the jolts and rough handling to which such kits are subjected incident to emergency or war time use.

Another object of the invention is to provide a first aid kit of the character described which when opened provides a complete portable hospital in which each of the various articles of equipment are presented in easily accessible, orderly arranged locations, whereby the physician may instantly locate the desired articles without first having to search through the kit.

Another object of the invention is to provide a portable first aid kit characterized by a work tray which, when the kit is closed, comprises a lateral partition member which precludes shifting of the various articles of equipment housed within the kit, and which when the kit is opened, comprises a sturdy, collapse-proof work table upon which the physician may place various articles of equipment, and the like.

Still another object of the invention is to provide in a first aid kit of the character described adjustable means for securely, though releasably mounting frangible articles, such as bottles and the like, whereby such articles are effectively cushioned against shock.

A further object of the invention is to provide in a first aid kit a vertically shiftable compartment or rack, normally housed within the kit, but which is adapted to be elevated quickly and easily to an operative position above the kit whereby its contents are rendered visible and instantly accessible to the physician.

Still a further object of the invention is to provide an adhesive tape dispensing rack wherein rolls of tape may be laterally shifted from a retracted to a fully extended position for rendering the tape easily accessible to the physician.

Still a further object of the invention is to provide a first aid kit having the hereinabove described characteristics which is particularly adapted for mass production, which is dirt and fluid tight, and which is structurally strong and durable.

These and other objects of the invention are attained by the means described herein, and disclosed in the accompanying drawings, in which:

Fig. 1 is a perspective view of a closed first aid kit embodying the present invention.

Fig. 2 is a view similar to Fig. 1 but with the lid opened revealing certain details of the kit.

Fig. 3 is a front view of the kit of Fig. 1 in a fully opened ready for use condition.

Fig. 4 is a vertical cross section through the closed kit of Fig. 1 along the line 4—4 of Fig. 2.

Fig. 5 is a vertical section taken through a portion of the bottle rack showing the construction of the bottle retaining means which comprises a detail of the present invention.

Fig. 6 is a vertical section taken on line 6—6 of Fig. 5.

Fig. 7 is a horizontal section taken along line 7—7 of Fig. 4.

Fig. 8 is a view of a vertical section on line 8—8 of Fig. 7, showing the relationship of the various rack elements when the rack is in a lowered position.

Fig. 9 is a view similar to Fig. 8 but showing the rack in an elevated or fully extended position.

With reference to Fig. 1, the first aid kit comprises a substantially rectangular trunk like case or outer housing 10, which may comprise a top 25 or lid member 11, opposed side walls 12, bottom 13, rear wall 14 and a two-piece front wall 15. Handles 16 and 17 may be provided on lid 11 and sides 12, as shown, to facilitate transportation of the kit from place to place. If desired, latching means denoted generally by the numeral 18, may be provided on the lid and front wall for securing the lid in a closed condition.

Front wall 15 comprises a pair of panels or doors 19 and 20, hingedly mounted one to the forward vertical edge of each side wall 12, by means of hinges 23 and 24 as shown. In the preferred embodiment of the invention, the inner edges 25 and 26 of panels 19 and 20 are adapted for overlapping engagement when the panels are closed, Figs. 1 and 2.

As illustrated in Figs. 2 and 3, each of the panels 19 and 20 comprises the rear wall of one of the so-called wing compartments 21 and 22, which are secured to and carried by said panels.

Each wing compartment may include top and bottom elements 150 and 151, and opposed side elements 152 and 153, as shown. The space bounded by these elements 152 and 153, and their respective rear walls may be suitably subdivided into a plurality of smaller or sub-compartments or pockets into which various medical supplies, and the like may be housed.

When the wing compartments 19 and 20 are nested (Figs. 1, 2 and 4), the bottom elements 151 overlie bottom wall 13 of the kit housing.

side elements 152 make coplanar abutment with side walls 12 of the kit, and side elements 153 are disposed in spaced parallel adjacency. Top elements 150 of the wing compartments are preferably in the plane of the top wall 135 of fixed compartment 35.

In order that the wing compartments may be securely retained in a nested condition when the kit is closed, a vertically reciprocable lock pin 27 may be provided on panel or door 28. Pin 27 may be slidably mounted within guide bearing members 31 and 32 carried by wing compartment 22, as shown. Pin 27 is normally urged upwardly by spring 28 which circumscribes said pin between collet 33 and guide member 32. The upper end of the lock pin is adapted to be contacted by lug 29 carried by lid 11 whereby the pin will be forced downwardly so that the lower end thereof will engage catch member 30 disposed on bottom 13. Stop member 34 fixedly secured to pin 27 is adapted to engage the lower face of bearing member 31 for limiting the upward travel of said pin when lid 11 is opened.

The interiors of the kit and each of the wing compartments are rendered accessible by swinging said compartments outwardly of the kit interior as shown in Fig. 3. It should be observed that when the compartments are thusly opened, the side elements 152 comprise a continuation of the kit side walls 12.

As clearly disclosed in Figs. 2, 3 and 4, a large central compartment 35 is provided between side walls 12 and disposed intermediate front and rear kit walls 15 and 14. This compartment may comprise a bottom 113, a rear wall 40 and a top member 135, said rear wall being spaced from and parallel to rear kit wall 14 as disclosed in Fig. 4. The interior of the compartment may be suitably subdivided into a plurality of smaller pockets A disposed on opposite sides of a central portion B which may include one or more drawers C and an adhesive tape compartment D.

It should be observed, Figs. 2 and 4, that when the wing compartments are nested their respective open faces are adjacent to and in communication with the forward open face of the central compartment 35. A tray member 36 is hingedly secured to kit bottom 13, as at 37 in such a manner as to be swingable between a vertical closed, and a horizontal or fully extended position. When in a vertical position, the tray comprises a common wall or partition member between the open faces of the wing compartments and the open portion of the central compartment. In the preferred embodiment of the invention, the surface area of the tray is substantially equal to the area of the forward open face of the central compartment whereby articles housed within the various pockets of the different compartments are precluded from being shifted from one compartment to another while the kit is being jostled around while closed.

It should be observed that tray 36 functions as a transverse reinforcing member for the kit housing when closed.

After the wing compartments have been opened, tray 36 is adapted to be lowered into a horizontal position, Fig. 3, to provide a work table extending forwardly of compartment 35 and between the wing compartments. Tray 36 is adequately supported in a horizontal position by reason of contact with that portion of the kit bottom which extends forwardly of hinge 37 to the forward free edge 38. In this manner, the need for auxiliary collapsible brace members ex-

tending between the tray and kit side walls may be dispensed with, without sacrificing stability and/or rigidity.

In the preferred embodiment of the invention, a vertically reciprocable bottle rack 41 is provided or housed within the space bounded by kit side walls 12, rear wall 14 and the rear wall 40 of compartment 35. The rack may comprise, generally speaking, a pair of spaced, parallel vertical end members 43 and one or more horizontal bottle shelves 42 disposed therebetween, as shown. When the kit is closed, the bottle rack may be lowered into the kit housing, Figs. 2 and 4, whereby to be covered by lid 11. When the kit has been opened, said rack may be elevated, Fig. 3, whereby the contents thereof are disposed above top 135 of the central compartment where they are rendered visible and easily accessible to the physician.

In the structure disclosed in Fig. 3, the rack includes two bottle shelves each of which may be disposed in the plane of compartment top 135, which functions as a shelf, upon which bottles from the rack may be placed.

Inasmuch as the structural features of opposite sides of the medicine rack are the same, only one side will be described for the sake of brevity. As disclosed in Figs. 7, 8 and 9, end member 43 is slidably mounted within a vertical track 44 which may include an outer wall 45, a pair of opposed ends 46, each of which terminates in an inturned lip 47 which is parallel to wall 45. A pair of spaced runners or guide rods 48 may be permanently secured to opposite ends of outer face 45, as shown. The runners are adapted for sliding engagement with the spaced corners defined by the intersection of rear wall 14 and side wall 12, and by the intersection of side wall 12 with the rear wall 40 of compartment 35. These corners each comprises a vertical guideway within which a runner or guide rod 48 of track 44 is adapted to slide.

Rack 41 is adapted to be supported in a partially elevated condition, wherein the upper of the two bottle shelves will be in a plane level with the top 135 of compartment 35, or in a fully elevated condition, as illustrated in Fig. 3, wherein the lower bottle shelf is level with the compartment top.

As disclosed in Fig. 9, end member 43 is provided with a catch member 49 which is adapted to engage the upper edge 51 of track member 44, which in turn is provided with a catch member 50 adapted to engage the upper edge of kit wall 12. Catch 49 may be yieldingly urged toward the track 44 by means of a spring such as 52, which may be carried by and secured to the end member as shown. Catch member 50 may likewise be yieldingly urged toward kit wall 12 by means of spring 53, one end of which may be fastened to track 44 by means of the bolts or rivets 54, or the like.

In order to preclude accidental or unintentional separation of end member 43 from track 44 when the rack is being withdrawn from the kit, a longitudinal closed ended slot 55 may be provided in the outer wall 45 of the track member with which an abutment member or pin 56, carried by end member 43, is adapted to cooperate.

In order to facilitate withdrawal of the rack from its lowered or retracted position, Figs. 2 and 4, a suitable knob or hand ring such as 57 may be provided, Fig. 3. When a lifting force is applied to ring 57, the end members 43 will move upwardly relative to tracks 44 until pins 56 en-

gage the upper closed end of the track slots 55. Catch members 49 are preferably wider than slots 55 (Fig. 4), therefore they will remain fully retracted for sliding contact with the inner side of outer wall 45 of tracks 44 until they clear the upper edge of the tracks at which time they will spring outwardly to engage the upper track edge. It should be noted that the tracks are still housed within the kit and only the upper portion, that is only the upper of the two bottle shelves 42, has been rendered accessible to the physician.

Further lifting via ring 51, will result in lifting the track members relative to the kit whereby to permit catch members 50 to engage the upper edge of the kit side walls, Figs. 3 and 9. The rack thus fully extended is sturdy and cannot be dislodged or knocked over by reason of the relationship between the lower end of the track members and the guideways in the kit corners. The raised rack may be lowered into the kit only after each pair of catch members 49 and 50 have been deliberately released from their engaging edges whereby the rack may be telescopically received within the kit.

As disclosed in Fig. 3, a plurality of bottles, denoted generally by the numeral 60, are supported on bottle shelves 42. With reference to Fig. 5, it is seen that each bottle shelf 42 comprises a plurality of parallel members held together by means of a plurality of spaced anchor pins 70. Shelf 42 comprises a baseboard 67, a sheet 66 of resilient cushioning material, such as sponge rubber, or the like, and a cover plate 63. The lower or bottom edge 61 of a bottle is adapted to be inserted through an aperture 62 provided in the cover plate 63, whereby to engage cushion member 66. In the preferred embodiment of the invention, the side edges of the resilient member are housed between a pair of upstanding side members 68 secured, one each, to a side of the baseboard 67, Fig. 6. The opposed side edges of cover plate 63 are preferably turned down to provide a pair of spaced flanges 69 disposed one in overlapping relationship with each upstanding side member.

The lower edge of a bottle is maintained within an aperture 62 and in contact with resilient member 66 by reason of the bottle cap 64 being wedged against the under side of a baseboard or other member disposed in spaced parallelism therewith. As disclosed in Fig. 5, the upper portion of the bottle cap is preferably conical in form and is adapted to fit within or engage a complementary shaped indentation or recess 65 provided in the underside of the next higher baseboard, as shown.

Varying degrees of compression may be applied to cushion member 66 by means of the adjustable anchor pins 70, each of which may comprise a head member 71 which may be turned by means of a screw driver, coin, or other tool relative to the body portion 70, for controlling the distance between the cover plate 63 and baseboard 67.

By reason of the adjustment obtainable by manipulation of anchor pins 70, it is possible to compensate for the "set" and deterioration which occurs in rubber products with the passing of time, whereby the necessity of removal and replacement of the cushion may be deferred indefinitely. Such adjustable anchorage pins likewise permit the individual physician to quickly and easily vary the force with which the bottles are anchored or secured within the rack as the conditions under which the kit are used vary.

The adhesive tape rack, disclosed in Fig. 4, may comprise a pair of spaced horizontal pas-

sageways 85 open at their front ends as at 86 and closed at their rear ends as at 87. A pair of spaced shaft receptive notches 82 and 83 are provided in the lower face 88 of the passageway. Notch 83, hereinafter referred to as the rear notch, may be disposed with its rear wall in vertical alignment with the rear end 87 of the passageway. Notch 82, hereinafter referred to as front notch 82, is preferably disposed as near to the forward edge 86 of the passageway as is practical.

When shaft 81 is seated in rear notch 83, the roll of tape 80 is in a retracted position, as illustrated.

When shaft 81 engages rear notch 83, the rolls of tape 80 are entirely housed within compartment D so as to clear tray 36 when it is in a vertical position. During those periods of time when tray 36 is in a lowered or horizontal position shaft 81 may be shifted forwardly from rear notch 83 to engage the front notch 82, for positioning the rolls of tape 80 in the projected position indicated by the broken lines, Fig. 4. When in this position the tape is presented to the physician in an easily accessible manner.

In the preferred embodiment of the invention, the side walls of the front notch are inclined backwardly at an angle of from 15 to 25 degrees from a vertical, as shown. This construction facilitates seating of shaft 81 therein when it is being shifted forwardly from rear notch 83. Such construction likewise permits the rolls of tape to be automatically lifted out of forward notch 82 and introduced into passageway 85 when the tray 36 is swung upwardly from a horizontal to a vertical condition. In order to insure proper seating of shaft 81 within the rear notch after being thus unseated from the forward notch, the lower face 188 of passageway 85 may be inclined toward the rear notch. Shaft 81 will roll or gravitate down the inclined face whereby to automatically engage the rear notch.

In the preferred embodiment of the invention the upper or top edge of the kit side walls 12 are provided with an inturned flange 200. This flange engages the outer edges of the upper wall 135 of the central compartment, and comprises a ledge under which the hinge-adjacent-edge of the top elements 150 of the wing compartments fit when they are nested within the kit. In this manner the wing compartments cooperate with and are so related to the bottom and side walls of the kit as to provide a sturdy kit having a high degree of resistance against crushing, distortion and the like.

With reference to Figs. 1 and 4, lid 11 is concave or dish shaped whereby to provide an area or fourth main compartment denoted generally by the numeral 90. The bottom and side walls of this compartment are formed by the lid whereas the compartment top may comprise a sheet of fabric 91 or other suitable material. It should be noted that when the lid is closed the compartment top 91 really becomes a bottom or supporting member. If desired, the top forming sheet of fabric 91 may be secured along its outer edge to lid 11 by means of slide fasteners 92, or by another suitable means which will permit the fabric to be securely though removably secured to the lid walls as shown. Sheet 91 controls access to compartment 90 in which may be housed a complete kit of surgeon's first aid implements, splints, large bats of cotton, and the like. In this manner, the kit interior is not cluttered up with these bulky

but essential articles although they are nevertheless easily available to the physician.

From the foregoing, it is apparent that I have provided a compact, sturdy, field-type first aid kit, which when closed comprises a rugged, reinforced, trunk-like box, adapted to withstand rough treatment and abuse without damage to or dislodgement of the articles and supplies housed therein. When opened, said kit provides a complete field hospital wherein each item of equipment is located for easy accessibility and instant use by the physician. The component parts of the kit are adapted to cooperate with one another so as to produce maximum rigidity with a minimum of parts, whereby the manufacturing and maintenance costs are reduced to a minimum.

It should be understood that various modifications and changes in the structural details of the device, such as, by way of example, providing suitable weather stripping to make the kit waterproof, may be made, within the scope of the appended claims, without departing from the spirit of the invention.

It should be noted that the bottle retaining means disclosed associated with rack 41 may, if desired, be provided in one or more of the other sub-compartments of the kit. Such bottle retaining means may be adapted to house articles ranging in size from small, easily frangible ampoules to large jug-like containers which are quite sturdy and practically indestructible.

In those instances where it is desirable to provide means to permit the shelves which define the various sub-compartments to be vertically adjustable, suitable slotted end brackets, not illustrated, may be utilized, as is the common practice.

What is claimed is:

1. A first aid kit of the class described, comprising a trunk-like structure consisting of a pair of opposed side walls, a bottom, a rear wall, a lid and a two panel front wall, each of said panels being carried by and hingedly secured to a side wall, a central compartment extending laterally between said side walls and being disposed intermediate the front and rear walls of said housing, said compartment including a rear wall spaced forwardly of the rear wall of said housing to form a pocket, and a top wall which forms a flat work shelf member spanning the opposed side walls of the structure at the top of said pocket, a medicine rack disposed within said pocket and mounted for movement to raised operative or lowered inoperative positions, said rack including a pair of spaced end members, a bottle shelf extending between and carried by said end members, and means for releasably maintaining said rack in a raised position with its bottle shelf in coplanar relationship to the flat work shelf member.

2. In a first aid kit of the class described, a rack for bottles and the like, said rack including a pair of vertically spaced bottle shelves between which bottles are adapted to be removably mounted, the lower shelf consisting of a baseboard, an apertured cover plate and a sheet of resilient material mounted between said baseboard and cover plate, means for securing said sheet of resilient material between said baseboard and cover member, the lower face of the upper shelf including a plurality of spaced indentations disposed one in vertical alignment with the center of each aperture in the lower shelf, the bottoms of bottles adapted to be inserted one each through an aperture in said cover plate to abut upon said resilient sheet, the tops of said bottles adapted to yieldingly engage one each an indentation of the upper shelf

whereby said bottles are securely, though releasably maintained between said shelves.

3. A device as specified in claim 2 in which the cover member and baseboard are secured together by means of adjustable elements whereby the distance between said cover member and baseboard may be increased or decreased to vary the compression of said sheet of resilient material for varying the degree of force with which said bottles are mounted and secured in place.

4. A first aid kit of the class described, comprising a trunk-like housing having opposed side walls, a bottom, a rear wall, and a pair of front walls hingedly secured one to the forward edge of each side wall, each front wall comprising the rear panel of a wing compartment attached to and carried thereby, each wing compartment including forwardly projecting top, bottom and side panels, said compartments adapted for movement to closed nested position inside of said housing, or to open extended position exteriorly of said housing with those side panels adjacent the hinged connection between the side panels and the forward edge of the side walls of the housing extending forwardly from and in the plane of their respective side walls, a central compartment permanently secured within said housing, said central compartment including a top wall spanning the opposite side walls of said housing, and a work shelf member hinged to the bottom wall of said housing for swinging movement to raised and lowered positions, said shelf member when in a raised position comprising a common division wall between the adjacent portions of the central compartment and the nested wing compartments and extending from the bottom wall of said housing to the top wall of the central compartment, said member when in a lowered position comprising a horizontal work shelf extending forwardly between the extended wing compartments to an obstructing relationship to prevent accidental or unintentional movement of said wing compartments from extended to nested positions.

5. In a first aid kit, a trunk-like receptacle consisting of a lid, bottom, opposed side walls, a rear wall and a two panel front wall, each of said panels being hingedly connected to the front edge of a side wall, a fixed compartment open at the front permanently secured within said receptacle and being disposed laterally between said side walls, a pair of wing compartments mounted one to each panel for movement to closed nested and open extended positions relative to said receptacle, each wing compartment including opposed top, bottom and side walls, the bottom and side walls of said receptacle extending forwardly beyond the plane of the front open portion of said fixed compartment by a dimension at least equal to the depth of said wing compartments whereby to overlie the outer side and bottom walls of each of said wing compartments when nested, a work shelf member hinged to the bottom wall of said receptacle along the front edge of the fixed compartment for swinging movement to raised and lowered positions, said work shelf member when in a raised position comprising a common division wall between and coextensive with the adjacent open faces of the fixed compartment and the nested wing compartments, said work shelf member when in a lowered position adapted to abut upon the forwardly extending bottom wall of the receptacle for establishing a horizontal work shelf member extending forwardly from said fixed compartment, projecting forwardly beyond the forward edge of the bottom wall of said recep-

tacle and outwardly between the extended wing compartments.

6. In a first aid kit, a trunk-like receptacle consisting of a lid, bottom, opposed side walls, a rear wall and a two panel front wall, each of said panels being hingedly connected to the front edge of a side wall, a fixed compartment open at the front permanently secured within said receptacle and being disposed laterally between said side walls, a pair of wing compartments mounted one to each panel for movement to closed nested and open extended positions relative to said receptacle, each wing compartment including opposed top, bottom and side walls, the bottom and side walls of said receptacle extending forwardly beyond the plane of the front open portion of said fixed compartment by a dimension at least equal to the depth of said wing compartments whereby to overlie the outer side and bottom walls of each of said wing compartments when nested, a work shelf member hinged to the bottom wall of said receptacle along the front edge of the fixed compartment for swinging movement to raised and lowered positions, said work shelf member when in a raised position comprising a common division wall between and coextensive with the adjacent open faces of the fixed compartment and the nested wing compartments, said work shelf member when in a lowered position adapted to abut upon the forwardly extending bottom wall of the receptacle for establishing a horizontal work shelf member extending forwardly from said fixed compartment, projecting forwardly beyond the forward edge of the bottom wall of said receptacle and outwardly between the extended wing compartments and in obstructing relationship thereto to preclude movement of said wing compartments to or toward nested position when said work shelf is in a lowered position.

7. A first aid kit of the class described comprising a trunk-like structure consisting of a pair of opposed side walls, a bottom, a rear wall, a lid and a front wall comprising a pair of panels each of said panels being carried by and hingedly secured to the front edge of a side wall, a central compartment extending laterally between said side walls and being disposed intermediate the front and rear walls of said housing, said compartment including a rear wall spaced forwardly of the rear wall of said housing to form a pocket, and a top wall which forms a flat work shelf member spanning the opposed side walls of the structure at the top of and in front of said pocket, a medicine rack disposed within said pocket and mounted for movement to raised operative or lowered inoperative positions relative to said work shelf member, said rack including two rows of vertically spaced bottle shelves, and means for releasably maintaining said rack in a raised position with either of said bottle shelves selectively in coplanar relationship with the flat work shelf member.

8. In a first aid kit of the class described, a rack for bottles and the like, said rack including a pair of spaced end members and a pair of spaced, upper and lower shelves spanning said end members, said lower shelf comprising a base-board, an apertured cover member and a resilient cushion member interposed between said base-board and cover member, said upper shelf having a plurality of bottle cap receptive recesses provided therein, said recesses being disposed in vertical alignment one each with an aperture of said cover member, and a bottle the height of which including its cap member is of a dimension

5 greater than the vertical distance from the uppermost surface of the resilient cushion member to the top of its associated cap receptive recess, said bottle adapted to be mounted between said shelves by inserting the bottom of the bottle in an aperture of the cover member of the lower shelf, after which the upper capped portion of the bottle is seated within its corresponding recess in the upper shelf, said resilient cushion member adapted to yieldingly urge the bottle toward the upper shelf for maintaining the bottle cap in its associated recess against accidental or unintentional displacement.

10 9. In a first aid kit a compartment including a pair of opposed side, front and rear walls, a vertically shiftable medicine rack mounted within said compartment, said rack comprising a pair of spaced end members, a plurality of spaced parallel transverse members interconnecting said end members, a movable track for each of said end members, guides for each of said tracks, and guideways formed within said compartment one for each guide, catch members carried by each of said end members, said catch members located intermediate the length of said end members and positioned to engage the upper edge of the track members of the end members to which they are attached, when the rack has been withdrawn approximately half way from said compartment, stop means carried by said end members and engageable with cooperative means on said tracks for precluding further upward movement of the end members relative to their respective track members, and whereby said track members are fixed relative to and for vertical movement with said end members as the rack is further withdrawn from the compartment to a fully raised position, and a second pair of catch members carried by and secured one each to a track member, and positioned to engage the upper edges of the compartment side walls when the rack has been withdrawn from said compartment to a fully raised operative position.

15 10. In a first aid kit a compartment including a pair of opposed side, front and rear walls, a vertically shiftable medicine rack mounted within said compartment, said rack comprising a pair of spaced end members, a plurality of spaced parallel transverse members interconnecting said end members, a movable track for each of said end members, guide rods secured to and carried by each track, guideways formed within said compartment one for each guide rod, said end members adapted for vertical sliding motion relative to said track members and said track members and their associated guide rods adapted for vertical sliding motion relative to said guideways, stop means carried by said end members and engageable with cooperative means on said track members for limiting the amount by which said end members may be lifted relative to their track members and whereby further lifting of said end members will result in lifting of the track members and their associated guide rods relative to their guideways as the rack is lifted to a fully raised operative position, said stop member being positioned to limit the free upward movement of the end members relative to their respective track members when the rack has been withdrawn approximately halfway from said compartment, and means for maintaining the rack in a half raised and a fully raised operative position.

20 11. In a first aid kit a compartment including a pair of opposed side, front and rear walls, a

vertically shiftable medicine rack mounted within said compartment, said rack comprising a pair of spaced end members, a plurality of spaced parallel transverse members interconnecting said end members, a movable track for each of said end members, guide rods secured to and carried by each track, guideways formed within said compartment one for each guide rod, said end members adapted for vertical sliding motion relative to said track members and said track members and their associated guide rods adapted for vertical sliding motion relative to said guideways, stop means carried by said end members and engageable with cooperative means on said track members for limiting the amount by which said end members may be lifted relative to their track members and whereby further lifting of said end members will result in lifting of the track mem-

bers and their associated guide rods relative to their guideways as the rack is lifted to a fully raised operative position, said stop member being positioned to limit the free upward movement of the end members relative to their respective track members when the rack has been withdrawn approximately half way from said compartment, and two sets of retaining members, one set secured to and carried by the end members and positioned to engage the upper edge of the track members for maintaining the rack in a half raised position, the second set secured to and carried by said track members and positioned to engage the upper edge of the side walls of the compartment for maintaining the rack in a fully raised operative position.

ROBERT R. SEATON.
